ATTORNEY.

UNITED STATES PATENT OFFICE.

ABRAHAM WEISINGER, OF NEWARK, NEW JERSEY, ASSIGNOR TO UNITED STATES TAXIMETER CORPORATION, OF NEW YORK, N. Y., A CORPORATION OF NEW JERSEY.

TAXIMETER.

Application filed January 12, 1924. Serial No. 685,916.

To all whom it may concern:

Be it known that I, ABRAHAM WEISINGER, a citizen of the United States, and a resident of Newark, county of Essex and State of New Jersey, have invented certain new and useful Improvements in Taximeters, of which the following is a specification.

This invention relates to an improved taximeter which is constructed to operate smoothly and efficiently and which is in duplicate for the respective indicator drums and which is adapted to have all the drums returned or re-set to zero by the operation of a single return handle.

15 The object of the invention is to provide such a meter which is accurate in that the parts are positively released and returned to the starting position and in which the respective units are easily assembled and operatively connected.

The invention is illustrated in the accompanying drawings in which Figure 1 is a front view of one unit of the taximeter and Figure 2 is a section on line 2-2 in Figure 25 1 looking in the direction of arrow *a*. Figures 3 and 4 are views similar to Figure 2 but with the parts in different positions. Figure 5 is a section on line 2-2 in Figure 1 but looking in the direction of arrow *b*. Figure 6 is a view similar to Figure 5 but with the parts in different positions. Figure 7 is a longitudinal section through Figure 1 and showing part of the next unit in dotted outline. Figure 8 is a detail section of the 30 parts shown in Figures 5 and 6.

In the construction shown the frame composed of the plate 10, the bearing plate 11 and the bearing plate 12 forms a support for the unit for registering and is suitably secured in the casing of the meter (not shown) as will be evident to one skilled in the art and the holes 13 receive screws by means of which the frame is fastened.

The finger 14 is the usual reciprocating arm operated by mechanism that is well known and is driven from the wheel of the vehicle. After a pre-determined amount of travel the finger 14 moves down once and pushes the arm 15 of the rocking lever 16 down against the influence of the spring 17 which is disposed so as to hold the lever 16 in normal position. When the lever is rocked back the pawl 18 at the end of lever moves the distance of one of the teeth 19 of 55 the ratchet 20. The rocking lever 16 moves

freely on the shaft 21 which shaft, however, is rotatable by other means as will be described hereinafter. The spring 22 holds the pawl 18 on the ratchet. The ratchet is secured on the jack shaft 23 which extends 60 through plates 11 and 12. A retaining pawl 24 is pivoted loosely at 25 and is held in place by the spring 26. On the shaft 23 is the drum 27 on the face 28 of which are the figures 29 which are successively placed in 65 view in the window or opening 30 in the plate 31 on the front of the taximeter. The drum has its flange placed over the plate 12 and some associated parts to occupy the minimum of space.

70 So far as described, the operation is relative to the advance of only one drum or one unit and as it is necessary to go from tens to hundreds, it is customary to place a fixed "0" to indicate the digits which is not 75 changed as the normal fare is in multiples of 10. The tens however, are indicated by the drum 27 and the next succeeding drum must operate one tooth at each complete revolution of the drum indicating tens so that the 80 meter can register to \$9.90, for instance.

To return the drum when it is released, I place a pinion 32 which is provided with a spring 33 fastened to the pinion and the stud 34 on which the pinion reciprocates. 85 The pinion 32 is in mesh with the pinion 35, and the pinion 32 is mutilated by a cutting away a part as at 36 so that excess pressure on the spring 33 is prevented.

The next succeeding unit is operated by a 90 rocker arm 37 secured so as to rock the shaft 21 to which it is secured as by a pin 38. At every complete revolution of the drum 27 and necessarily of its shaft 33, the cam 39 moves from the position shown in 95 Figure 5 and in its rotation shoves the rocker arm 37 over until it snaps over the nose 40 and the spring 41 operates it and the shaft 21 to which the next unit connected by having its rocking lever 16 secured to the shaft by the pin 42 or its equivalent.

When the cam 40 moves the rocker arm 37 it rocks the shaft 21 and the rocking lever 16 of the next unit far enough to 105 move its pawl 18 over one tooth of its ratchet and the next drum advances one figure. The rocker arm of the said next unit is not operated except by its own cam 39 as the shaft 21 is divided by a loose connec- 110

tion 43 as will be seen from Figure 7 in which figure the rocking lever and rocker arm of said next unit are shown in dotted outline.

5 When the meter is to be re-set, the flag arm or handle 44 rotates the shaft 45 which has a finger 46 which is disposed so as to bear on the studs 47, 48 and 49 of the pawl 18, rocking lever 16 and pawl 24, respectively, in each unit so that all the ratchets are relieved of these and the spring 33 in each unit forces the mutilated pinions 32 to rotate the pinion 35 and drums are all rotated back to zero, being halted in each 15 unit by its rocker arm 37 which acts as a stop.

It will be seen from this description that the repeated rotation of the drums as in a long ride will not strain the return springs 20 33 as the spring can not be wound to excess as the open place 36 will prevent any fur-

ther rotation of the mutilated pinion beyond the position shown in Figure 8.

Excess throw of the pawl 18 is prevented by the stud 50. 25

Minor changes can be made in the construction without departing from the scope of the invention.

I claim:

In a taximeter having a drum, a rocking lever, a pawl rotatable with the drum and a retaining pawl normally engaging the ratchet, a re-setting device including a shaft and a finger on the shaft disposed so as to engage the lever and both pawls to simultaneously swing them all to inoperative position. 30 35

In testimony that I claim the foregoing, I have hereto set my hand, this 14th day of November, 1923.

ABRAHAM WEISINGER.
